Primary Examiner — Elizabeth Albert(74) *Attorney, Agent, or Firm* — Wright Lindsey Jennings;
Meredith Lowry(57) **CLAIM**

The ornamental design for a writing and drawing instrument, as shown and described.

DESCRIPTION

FIG. 1 is a top perspective view of a writing and drawing instrument showing my new design;

FIG. 2 is a right side elevational view thereof, the left side being a mirror image thereof;

FIG. 3 is a front elevational view thereof;

FIG. 4 is a back elevational view thereof;

FIG. 5 is a top plan view thereof; and,

FIG. 6 is a bottom plan view thereof.

The two features in broken lines are included to show unclaimed outlines on claimed surfaces and the broken lines form no part of the claimed design.

1 Claim, 3 Drawing Sheets**FIG. 1**

FIG. 2**FIG. 3****FIG. 4****FIG. 5****FIG. 6**
